UNITED STATES PATENT OFFICE.

HARRY J. MARTIN, OF FORT DODGE, IOWA.

LANCE-PIECE FOR PYROTECHNICS.

1,263,785.

Specification of Letters Patent. Patented Apr. 23, 1918.

Application filed October 4, 1916. Serial No. 124,008.

To all whom it may concern:

Be it known that I, HARRY J. MARTIN, citizen of the United States of America, and resident of Fort Dodge, Webster county, 5 Iowa, have invented a new and useful Lance-Piece for Pyrotechnics, of which the following is a specification.

The object of this invention is to provide an improved construction for a frame for 10 pyrotechnical set pieces of lance construction.

A further object of this invention is to provide improved means for mounting and assembling the members of a lance set piece to 15 facilitate contracting the piece for packing, storage, shipment and the like.

A further object of this invention is to provide improved means for collocating and 20 assembling the members of a lance set piece in such manner that the set piece is readily expansible and contractible and capable of packing in a package of minimum dimensions.

My invention consists in the construction, 25 arrangement and combination of elements hereinafter set forth, pointed out in my claims and illustrated by the accompanying drawing, in which—

Figure 1 is an elevation of a set piece 30 constructed according to my invention and representing a flag, the piece being shown in extended position, with a portion broken away to economize space. Fig. 2 is a bottom elevation of the same piece in contracted 35 position. Fig. 3 is an elevation of a portion of another piece embodying my invention and representing a conventional legend.

In the construction of pyrotechnical set 40 pieces embodying the lance and similar cases for fixed fires, it has been customary to construct a rigid lattice-work frame of sufficient dimensions to accommodate the piece, and to mount the cases on strips of ratan or 45 similar flexible or partially flexible substance bent to the desired outlines and secured to said frame. The consequence of this rigid construction of the frame was and is that a very serious problem is presented to the manufacturer when it comes to 50 packing the piece for transportation, as the frame is often so large as to be cumbersome

and hard to handle; and as the piece is by nature quite fragile, it is necessary to provide a strong package therefor, the dimensions of which, in many instances, are so great as to entail considerable expense both 55 in construction and handling. This problem has been alleviated or solved in part at times by building the frame so that it may be folded once at or about the middle, so that the greatest dimension of the package 60 may be reduced by about half, at the expense of the least dimension, which would be about doubled. This expedient involved the breaking and splicing of ratans and of 65 matches or fuses connecting the various lances, and increased the labor of erecting or setting up the piece, after arrival at its destination.

My present invention is designed to overcome 70 the difficulty above outlined with regard to the packing of the set pieces, without at the same time adding to the expense and trouble of erecting the same.

In the construction of the device as shown 75 a plurality of frame bars 10 are provided, which may be of any desired number to accommodate the piece to be constructed. The frame bars 10 are spaced apart and arranged in approximately upright position, 80 and are either parallel, as shown in Fig. 1, or partly parallel and in part inclined relative to one another, as shown in Fig. 3; or any other desired arrangement may be given to the said bars to attain the desired end, so 85 that they are arranged in the same plane. Leaders such as stay wires 11, 12 are provided and preferably are arranged parallel to each other, and crossing and fixed to the several frame bars 10. On the frame bars 90 10 are mounted in a common manner the lances such as 13, or other cases, connected, also in a common manner, by fuses of quick-match such as 14, to produce the desired design; and these cases may, of course, be varied as to color, construction, and the like, 95 as desired. In the design shown in Fig. 1 I have illustrated the representation of a flag constructed according to my invention, in which the lances to represent the various 100 portions of the flag are carried by parallel upright frame bars 10, while the staff of the

flag is represented as being borne on a special frame bar which may be designated as 10^a. As the special bar 10^a extends materially beyond the general parallelogram of 5 the body of the design, it is desirable to provide means for folding or contracting it, and to this end I have shown it pivotally connected at its upper end to the lower end of an outermost frame bar 10 by means of a 10 hinge 15, preferably formed of a strip of pliable or semi-flexible material such as tin.

It will be noted that the frame constructed as above described has no rigid cross-bars, and that there is nothing to prevent its collapse 15 or contraction by approximation of the upright bars 10. When it is desired to contract the piece for packing or the like the leaders or stay wires 11, 12 are in turn grasped between the thumb and finger and 20 given a turn or fold, as indicated at 16 in Fig. 1, not exceeding a quarter turn, to bring adjoining frame bars 10 into approximated relations. This operation is performed on the leaders or stay wires between each successive 25 pair of frame bars, until the entire frame is materially contracted and its members brought nearly together in the same plane. Then manual compression may be employed, acting against the two outermost bars 10, to further contract the frame and bring the individual members 10 into still more intimate relations, as indicated in Fig. 30 2. The special bar 10^a may be brought into parallel relations with the outermost bar 10 by flexing the hinge 15, whereupon the whole piece is in contracted position such that it occupies a space having two dimensions, height and thickness, not greater than that of the individual members (together with 35 40 the pyrotechnical devices carried thereby), and a third dimension only a fraction that of the length of the device when extended. During such operation the fuses 14, being flexible, are doubled or looped between or 45 near the ends of the respective frame bars. This applies, of course, only to such portions 50 of the fuses as are between the several frame bars. The entire piece may then be packed in a package of relatively small dimensions, compared to the extended dimension of the set, particularly as to the greatest dimension 55 thereof, and the consequent saving in cost and convenience in handling, will be of great advantage. When it is desired to extend and 60 erect the set the outermost bars 10 are grasped and moved away from each other, the leaders or stay wires gradually straightening, and finally placing a limit on such movement, as designed by the maker. As 65 the loops or turns 16 given to the leaders or stay wires in the contracting operation do not exceed a quarter turn, there is little if any danger of kinking or knotting them in

the extending operation. The staff of the flag, represented by the bar 10^a, may be 65 brought to position by again flexing the hinge 15. As the hinge 15 is, in most cases, actuated but twice, or at most a very few times, it may be formed of the strip of tin or other similar material, as above suggested, 70 at very small cost, and the danger of its breaking under the strain of continued flexing need not be considered.

When extended the piece may be secured in position on the desired supports by nailing or otherwise securing the outermost bars 10 of the body, and the special bar 10^a, the stay wires 11, 12 being extended to their full length and supporting the intermediate bars 10 in proper and desired position. The 80 points of attachment of the various frame bars 10 on the leaders or stay wires may be varied to secure the desired general outline or design, as indicated and suggested in Fig. 1. 85

In Fig. 3 I have shown a slightly different arrangement of some of the frame bars 10 in the formation of a word or legend such as "Welcome," in which the general position of the bars is upright, while certain of said bars 90 are inclined somewhat in one direction or another to form letters having inclined members, such as "W" and "M." The general arrangement, and the operation of contracting, expanding, and securing, is the same 95 as above described. It will be noted that a greater loop or twist must be given to the leaders or stay wires in some cases between inclined bars, and a lesser turn or twist in still other places, said bars being brought to 100 parallel positions when contracted.

It will be understood that other arrangement may be employed for the frame bars to construct other designs, legends and the like, such as placing the bars in horizontal 105 or recumbent positions, in any locations retaining the characteristic of paralleling the bars in contracted positions.

I claim as my invention—

1. A device of the class described, comprising frame bars arranged in the same general direction, flexible leaders crossing and fixed to each of said frame bars, and pyrotechnic devices carried by said frame bars. 110 115

2. A device of the class described, comprising rigid frame bars arranged in the same general direction, flexible members fixed to and connecting said frame bars and permitting them to be brought into compact 120 parallel relations, a frame bar pivotally connected to one of the first-mentioned bars, and pyrotechnic devices carried by all of said bars.

3. A device of the class described, comprising a plurality of rigid frame bars ar-

ranged in approximately parallel relations and normally spaced apart, flexible members or leaders crossing and fixed to said frame bars and adapted to be looped or flexed between and thereby permitting approximation thereof at times and also adapted to be extended and thereby limiting separation of

said bars, pyrotechnic cases carried by said bars, and flexible fuses connecting the cases on the several bars.

Signed by me at Fort Dodge, Iowa, this 26th day of May, 1916.

HARRY J. MARTIN.
